C. P. BEACH.

ARBOR PRESS.

APPLICATION FILED FEB. 24, 1919.

1,373,588.

Patented Apr. 5, 1921.

Charles P. Beach. Inventor.

By his attorneys.

Emory, Booth, Janney, & Varney.

UNITED STATES PATENT OFFICE.

CHARLES P. BEACH, OF LITTLETON, NEW HAMPSHIRE.

ARBOR-PRESS.

1,373,588.

Specification of Letters Patent. Patented Apr. 5, 1921.

Application filed February 24, 1919. Serial No. 278,813.

To all whom it may concern:

Be it known that I, CHARLES P. BEACH, a citizen of the United States of America, residing in the town of Littleton, in the county 5 of Grafton and State of New Hampshire, have invented an Improvement in Arbor-Presses, of which the following is a specification.

My invention relates to arbor presses, the 10 object of the invention being to provide devices of the character specified which may be readily built up and as readily disassembled, and which are simple and economical in construction, and efficient and positive in 15 action.

By way of example, I have shown a preferred embodiment of my invention in the accompanying drawings, wherein—

Figure 1 is a plan view of a removable 20 base plate that may be incorporated in such a press;

Fig. 2 is a side elevation, partly in section, of the arbor press in assembled form and incorporating the said base plate;

25 Fig. 3 is a similar view showing the arbor press used in conjunction with a plurality of grooved supporting members supported on the base plate and with a grooved block on the operative end of the operating member of the press;

Fig. 4 is a detailed perspective view of one of such grooved supporting members;

Fig. 5 is a similar view of the said grooved block.

35 Referring to the foregoing illustrative embodiment, the press includes a detachable base plate 1, preferably of hexagonal form and containing a centrally disposed aperture 2. Adjacent the periphery of the base plate, 40 the same is provided with a plurality of grooves or recesses 3, said grooves being here shown as disposed in alternate sides of the base plate 1 on the lower surface thereof. The upper surface of the base plate may, if 45 so desired, be provided with a plurality of depressions or recesses 4 for containing the grooved supporting members 5 which will be hereinafter described in greater detail.

While the base plate of my invention may 50 be incorporated with various devices to produce an arbor or similar press, I prefer to use the same with a device such as the gear remover described and claimed in my co-pending application entitled "Gear removers," filed July 26, 1917, and bearing Serial 55 No. 182,847, having matured into Patent No.

1,313,511, dated Aug. 19, 1919, since the combination of the base plate and of such a gear remover results in marked advantages of simplicity, manipulation, and ease of disassembling the press.

Cooperating with the grooves 3 of the base plate 1, as by having their operative extremities 6 positioned in such grooves, are a plurality of gripping members 7, preferably pivoted to a support 8, as at 9.

The members 7 are provided at their inner ends with the projections 10 for engagement with the lugs 11 of a sliding member 12, slidably supported within a sleeve 13 forming a part of member 8. Passing through the sleeve 13, as by being threaded through it, is the operating member 14 of the press, the same consisting of a screw having the square end 15 for engagement with a wrench 70 or similar tool, and the cone-shaped end 16, for engagement with the work.

It will be apparent that by sliding member 12, the ends 6 of members 7 will be actuated toward or away from each other through the 80 mediation of projections 10 and their engagement with lugs 11 of member 12. In order to lock the members 7 in any desired position, as with the extremities 6 of such members in grooves 3 of the base plate 1, I 85 provide locking means consisting of an operating handle 17 which is threaded upon and secured to a bolt 18 on which are mounted a plurality of nuts 19, respectively threaded left and right hand upon the bolt 18. The 90 arrangement is such that the manipulation of the operating handle 17 acts to exert or release the pressure of the nuts 19, which are disposed in a recess in the sleeve 13, on or from the sliding member 12. Obviously any 95 other form of locking member may be employed.

The grooved supporting members 5, which may be detachably positioned in the recesses 4 on the upper surface of the base plate 1, 100 preferably comprise V-shaped blocks 20 having the grooves 21 in the upper faces thereof. The grooves of the members 5 are positioned so as to be in alignment with each other and with the groove 22 of a V-shaped cap or head 23 which may be supported on the cone-shaped end 16 of the operating member 14. For this purpose the head 23 is provided 105 with the recess 24.

The manner of assembling and using the 110 illustrative embodiment of my invention here shown and described by way of example

merely, will be substantially clear from the foregoing description. The sliding member 12 is manipulated by means of pressure exerted on the operating member 14 to open or spread apart pivoted members 7, the locking means 17, 18, and 19 being in open position, until the ends of members 7 may freely enter grooves 3 of base plate 1. The locking means are then actuated to lock members 7 in the desired position. The press is now in assembled position and may be used in the well known manner by manipulating screw 14.

The arrangement of the grooves or recesses 3 with respect to the plate 1 and the operative extremities 6 of the gripping members 7 shown in the foregoing illustrative embodiment is of considerable practical advantage in that it permits the base plate 20 and the parts carried by it to be supported flat and firmly on the bench or support used for the press.

When it is desired to use the press for straightening bent rods or pipes, members 5 are placed on base plate 1, and head or cap 23 is placed on the cone-shaped end 16 of screw 14 so that grooves 21 of members 5 and the groove 22 of member 23 will be in alinement, as more clearly shown in Fig. 3 of the drawings. With the pipe or other article to be straightened, here designated by reference character 25, engaging the alined grooves of members 5 and 22, the operation of the screw 14 in the well known manner 35 serves to straighten the article 25.

In order to disassemble the device, the locking means 17, 18 and 19 are opened, permitting sliding member or sleeve 12 to be actuated to spread members 7, to withdraw 40 the ends 6 from grooves 3 of base plate 1.

It is, of course, to be understood that my invention is not to be limited to the particular embodiment thereof, here shown and described for purposes of illustration only.

45 What I claim is:

1. In an arbor press, a base plate having a central aperture and a plurality of grooves adjacent the periphery of said member, in combination with detachable power-apply-

ing means comprising a supporting member, 50 a plurality of gripping members pivoted to said supporting member, an operating member associated with said supporting member, means associated with said supporting member and actuated by the same for causing 55 said gripping members to approach each other, and means for detachably locking said gripping members in position in the grooves of the base plate.

2. In an arbor press, a base plate having 60 a plurality of grooves adjacent the periphery thereof, a plurality of grooved supporting members supported on one face thereof, in combination with detachable power-applying means comprising a supporting 65 member, a plurality of gripping members pivoted to said supporting member, an operating member associated with said supporting member, means associated with said supporting member and actuated by the 70 same for causing said gripping members to approach each other, and means for detachably locking said gripping members in position in the grooves of the base plate.

3. In an arbor press, a base plate having 75 a plurality of grooves adjacent the periphery thereof, a plurality of grooved supporting members supported on one face thereof, in combination with detachable power-applying means comprising a supporting 80 member, a plurality of gripping members pivoted to said supporting member, an operating member associated with said supporting member, means associated with said supporting member and actuated by the 85 same for causing said gripping members to approach each other, and means for detachably locking said gripping members in position in the grooves of the base plate, said operating member being provided at the operative end thereof with a grooved block 90 co-operating with said grooved supporting members.

In testimony whereof I have signed my name to this specification this 18th day of 95 February, 1919.

CHARLES P. BEACH.
